United States Patent Office

Des. 219,115

Patented Nov. 3, 1970

219,115

TELEVISION CAMERA

Donald E. Leman, Rosemont, Ill., assignor to Ampex Corporation, Redwood City, Calif., a corporation of California

Filed Jan. 2, 1970, Ser. No. 20,743

Term of patent 14 years

Int. Cl. D16—02

U.S. Cl. D61—1

FIG. 1

FIG. 2

FIG. 1 is a front, left side and top perspective view of a television camera embodying my new design; and

FIG. 2 is a rear and left side perspective view of the camera of FIG. 1, the right side being a mirror image of the left side, and the bottom being conventionally plain.

I claim:

The ornamental design for a television camera, substantially as shown and described.
